UNITED STATES PATENT OFFICE.

GEORGE KAMP, OF UTICA, NEW YORK.

GRATE.

SPECIFICATION forming part of Letters Patent No. 253,293, dated February 7, 1882.

Application filed June 10, 1881. (Model.)

To all whom it may concern:

Be it known that I, GEORGE KAMP, a citizen of the United States, residing at Utica, in the county of Oneida and State of New York, 5 have invented certain new and useful Improvements in Grates; and I do hereby declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 represents a top plan view of my 15 improved grate in position in a stove or furnace. The drawings show a portion of the upper oscillating grate broken away to show the anti-friction bearings or rollers upon which said upper grate rests. Fig. 2 is a diametrical 20 section from front to rear of Fig. 1. Fig. 3 represents a detached view, in perspective, of the 25 rear hinge of the lower grate. Fig. 4 is a detached view, in perspective, of the anti-friction support of the upper grate. Fig. 5 is a 30 detached view, showing the hook that supports the forward part of the lower grate. Fig. 6 is a transverse section taken through one of the anti-friction supports. Fig. 7 is a plan view, showing more perfectly the lower grate and its 35 connections.

Similar letters of reference in the several drawings denote similar parts.

My invention has for its object the provision 35 of a simple and easily-operated two-part grate for stoves and furnaces, whereby ashes, cinders, &c., resulting from the combustion of the various kinds of fuel shall be quickly and thoroughly removed from the mass of burning material within such stoves or furnaces; and to 40 the accomplishment of the above end it consists in a two-part grate the upper section of which has a motion around its own center, which is coincident with the center of the grate as a whole, while the center of motion of the 45 lower or oscillating section is at the rear of the grate, and in the means whereby said motions are imparted to the grates, substantially as hereinafter set forth and described.

It also consists in means whereby to lessen 50 the friction of parts while the grate is being operated, as hereinafter described.

Referring to the drawings, A represents the base of an ordinary stove or furnace.

A' A' A' represent bearings or supports for the upper oscillating grate, B. The bearings 55 A' are preferably three in number, cast with or otherwise secured to the base A, and projecting inwardly from the same, as shown. The inner or free ends of the bearings A' are provided with recesses a to receive and hold rollers or balls a'. The sides a² a³ of said recesses are respectively convex and concave, thus conforming to the outer surface of a flange, b, which projects downwardly from the under surface of the grate B. Suitable openings, a⁴ a⁵, are 65 provided at the bottom and at each side of the recesses a for the escape of such ashes or cinders as may fall into said recesses. Openings a⁶ are also provided between the sides a³ of the recesses and the sides of the stove for a similar purpose. 70

The upper oscillating grate consists of an annular part, B, concave upon its upper side, as shown in Fig. 2. The lower surface of the ring B is provided at each side with flanges b 75 b', the inner flange, b, being somewhat deeper than the outer flange, b', and the outer surface thereof bearing against the side a² of the recess a, as above described, thus keeping the ring B in proper position at all times. The grooved 80 portion b² of the ring B rests upon the rollers or balls a', and thereby lessens greatly the friction of parts when the said ring is oscillated, as will be readily understood. Short radial arms or fingers b³ b⁴ project from the outer and 85 inner surfaces of the ring B, the latter, b⁴, of which are longer than the former, and terminate near the upper surface of the lower grate, C, as shown.

Attached to and projecting outwardly from 90 the ring B, and at the front thereof, is a handle, B', whereby said ring is operated.

Extending downwardly from the handle B', and near its juncture with the ring B, is a stud, b⁵, the lower portion of which terminates 95 in a hook, b⁶, the purpose of which will be hereinafter described.

The body of the lower grate, C, is similar in form and construction to those in common use, consisting of a ring, c, having straight ribs 100 c', V-shaped in cross-section, extending from front to rear thereof. The grate C is provided

at its rear side with a bifurcated lug, c^2 , in which, at c^3 , is pivoted a tongue, c^4 , provided at its free outer end with a downwardly-projecting stud, c^5 , that enters a suitable aperture, a^7 , in a lug, A^2 , projecting inwardly from the base A. The pivotal point c^3 in the lug c^2 allows up-and-down motion to the front or forward part of the lower grate, while the stud c^5 , pivoted in the lug A^2 , allows lateral motion to said forward portion of the grate, as will be readily understood.

Projecting from the forward part of the grate C is a downwardly and outwardly curved arm, C', the outer free end of which is provided upon its under surface with a shouldered portion, c^6 , whereby the arm is prevented from slipping out of the hook b^6 , in which said arm C' normally rests.

To operate the grate the handle B' is moved to and fro, such movement causing the upper part, B, of the grate to oscillate upon its bearings A', while the lower grate, being attached at its rear end to the base of the stove and at its forward end to the said upper part, B, will be caused by such movement of the handle B' to move to and fro laterally, the result of which compound movements will be to thoroughly sift the ashes, cinders, &c., through the openings in the grate and into the ash-pan, as will be readily understood. To damp the contents of the stove, raise the arm C' out of the hook b^6 , thus allowing said grate C to drop.

Having thus described my invention, what I claim, and desire to secure by Letters Patent, is—

1. A two-part grate consisting of an upper section having a motion around its own center coincident with the center of the grate as a whole, and a lower section having its center of motion at the rear of the grate, substantially as and for the purpose set forth.

2. In a two-part grate, the upper part consisting of an annular section, B, concave upon its upper side, and provided with radial fingers $b^3 b^4$, flanges $b b'$, and handle B', having depending stud b^5 and hook b^6 , substantially as described.

3. In a two-part grate, the combination of the grate C, having arm C' and bifurcated lug c^2 , with the tongue c^4 , pivoted at its forward end in said lug c^2 , and provided at its rear end with a downwardly-projecting stud, c^5 , whereby to pivot said tongue to the lug A^2 upon the base of the stove, substantially as described, for the purpose specified.

4. In a two-part grate, the combination of the lug A^2 , tongue c^4 , and bifurcated lug c^2 , attached to the grate C by pivot c^3 , whereby the said grate is capable of being moved up or down or from side to side, substantially as described.

5. In a two-part grate, the combination of the upper rotary section, B, provided with radial fingers $b^3 b^4$, flanges $b b'$, handle B', having depending stud b^5 and hook b^6 , with the lower laterally-moving grate, C, provided with bifurcated lug c^2 and curved arm C', substantially as described.

6. In a two-part grate, the supports A', having their outer ends provided with recesses a to receive and hold friction rollers or balls a' , and provided also with suitable openings, $a^4 a^5$, for the escape of ashes, cinders, &c., in combination with the lower grooved surface, b^2 , of the annular section B, substantially as described.

In testimony whereof I affix my signature in presence of two witnesses.

GEO. KAMP.
